VEGETABLE SIZING APPARATUS

William J. Zink, Birmingham, Ala., assignor to
Mathews Conveyer Company, Ellwood City, Pa.,
a corporation of Pennsylvania

Application August 11, 1937, Serial No. 158,563

2 Claims. (Cl. 209—84)

This invention relates to vegetable sizing apparatus and is directed more particularly to an apparatus for sorting onions, tomatoes and potatoes according to their relative sizes.

The primary object of the present invention is to provide a grading device unit that is simple in construction, inexpensive to manufacture, and highly efficient in operation, and which may be operated alone to sort two different sizes, or which may be easily and quickly connected to additional similar units to provide an apparatus capable of sorting a plurality of sizes of vegetables.

Another object is to provide an apparatus of the character which shall effectively sort vegetables such as tomatoes and potatoes, without bruising, scraping, or otherwise injuring the vegetables during their passage through the device.

A further object is to provide a sorting apparatus wherein the vegetables will be effectively separated according to size and the different sizes will be separately discharged from the apparatus into bags or other suitable containers.

With the foregoing and other objects in view, the invention may be stated to consist in the various novel features of construction and arrangement or combination, all of which will be fully described hereinafter and pointed out in the appended claims.

In the drawings accompanying and forming a part of this application,

Figure 1 is a side elevation of a sizing apparatus constructed in accordance with my invention and illustrating a three unit machine;

Figure 2 is a top plan view thereof; and

Figure 3 is a side elevation of one of the sizing units.

A sizing apparatus constructed in accordance with my invention comprises either a single unit capable of sorting vegetables according to two different sizes, or a plurality of units operatively connected together to form a device that is capable of sorting vegetables according to a plurality of sizes.

One of the sizing units is illustrated in Figure 3 and comprises a suitable framework consisting of vertically disposed members 1, horizontally disposed bracing members 2, and upwardly inclined bracing members 3. These members may be formed from any suitable material, but for economical reasons, and to facilitate connecting several units together, I preferably use angle iron for these members.

Mounted within the framework is an endless sizing belt 5. This belt is preferably of standard

construction and comprises formed wires which define diamond shaped openings of a predetermined size. The belt 5 is upwardly inclined and passes around rollers 6 and 7. Roller 6 is mounted on a shaft 8 which is journaled in bearings 9 that are secured to uprights 1, and roller 7 is mounted on a shaft 10 which is journaled in bearings 11. The bearings 11 are slidably mounted on the upwardly inclined angle members 3 by means of bolts 12 that are engaged through slots (not shown) in the angle iron members 3. Each bearing is formed with a downwardly projecting flange 13, and a bolt 14 projects therethrough and also through an angle bracket 15 that is fixed to the member 3. Each bolt is fitted with a nut 16 so that by adjusting these nuts, on the bolts 14, the tension on the sizing belt may be varied.

Suitable side panels 18 are fastened to the upwardly inclined members 3 to maintain the vegetables on the sizing belt 5 while passing through the apparatus. As shown in Figure 3, each panel 18 extends from a point adjacent the lower roller 7 to a point beyond the upper roller 6. The panels 18 are each recessed to receive the roller 6, and these panels extend beyond the roller 6 to form a delivery chute 19.

Arranged beneath the upper run of the sizing belt is a hopper shaped platform 22 which receives the vegetables that drop through the openings in the sizing belt. This platform is fitted at its lowest point with a delivery chute 23 which projects to one side of the apparatus and is supported by vertically disposed angle members 24 extending between members 2 and 3. If desired, a belt conveyer (not shown) may be substituted for, or used in connection with the delivery chute 23 for transporting the articles to any desired location.

In Figures 1 and 2, I have shown a sizing apparatus composed of three units similar to that described above. The vegetables are fed to the sizing apparatus by a horizontally disposed conveyer or picking unit, the discharge end of which is indicated generally at 25, although it will be understood that any suitable feeding arrangement may be used. The vegetables are received on the lower end of the first unit, and as they travel upwardly on the open mesh belt, the smaller ones drop through the openings in the belt onto the platform 22 and are discharged from chute 23 at the side of the unit. In the case of tomatoes, the openings in the belt of the first unit are preferably 203/16 inches 55

which is the size used for tomatoes known as "7-7's" to drop through.

- 5 The tomatoes which are retained on the belt of the first unit are carried upwardly and are discharged on the lower end of the second unit. The openings in the belt of the second unit are preferably 2½ inches which allows tomatoes known as "6-7's" to drop through the belt and be discharged through the side chute of this unit.
- 10 The larger tomatoes are carried upwardly on the belt and are discharged onto the lower end of the third unit. This third unit is provided with a belt having openings preferably 2¾ in diameter to allow tomatoes known as "6-6's" to drop through and be discharged from the side chute of the unit.
- 15 If a still further separation is desired, a fourth unit could be easily added as will be explained hereinafter, and this fourth unit would have openings preferably 3 inches in diameter to allow 20 tomatoes known as "5-6's" to drop through.

By referring to Figures 1 and 2, it will be observed that a sizing unit constructed as shown in Figure 3, may be used alone where a separation of two sizes is desired, or a plurality of these 25 units may be easily and quickly connected together to provide a multiple sizing apparatus. When a plurality of units are used, the uprights adjacent the lower end of the belt are engaged with and connected to the uprights of an adjacent 30 unit, which latter uprights are adjacent the upper roll 6. These abutting uprights are connected together in any suitable manner, as by bolts 28. The discharge chute 19 of one unit is connected to the side panels 18 of the adjacent 35 unit by plates 29 (Figure 3) or in any other suitable or approved manner. The discharge chute 19 of the last unit may be fitted with a side delivery chute 30, as shown in Figures 1 and 2, if desired. Between each unit, the discharge chute 40 19 is preferably fitted with a metal bottom slide 31 having a rubber covered surface to facilitate transfer of the tomatoes from the discharge end of one unit onto the receive end of the adjacent unit without bruising or otherwise damaging the tomatoes.

45 As shown in Figures 1 and 2, the several sizing belts are driven from a single source of power in the form of a gear head motor 35 which is supported on channel members 36 that extend transversely between angle members 2. A chain 37 connects the motor sprocket 38 with a sprocket 39 on shaft 8 of one of the units. This shaft is also fitted adjacent each end with smaller sprockets 40 and 41. Sprocket 40 is connected by means of a chain 42 with a similar sprocket 50 43 on the shaft 8 of an adjacent unit. Similarly, sprocket 41 is connected by a chain 44 with a sprocket 45 on the other adjacent unit, and this unit is shown fitted with a sprocket 46 that drives the picker conveyer 25 through a chain 47. It is thus obvious that by similar driving 55 sprockets and chains, additional units may be connected to the apparatus. When a single unit only is used, the motor 35 drives only the sizing belt of that unit, and if desired, the picking unit in the manner described above. It will thus be apparent that a unit sizing apparatus constructed in accordance with my invention may be economically manufactured and provides an exceptionally flexible and desirable arrangement whereby one unit alone may be used, or any desired number of such units may be easily and quickly assembled to provide an apparatus ca-

5 pable of multiple separation according to a plurality of sizes. The apparatus also provides the additional advantage that the small grower and shipper may add to his apparatus from time to time without his original unit becoming obsolete.

What I claim is:

1. A sizing apparatus comprising a plurality of similar units adapted to be used in connected series, each unit including a rectangular framework having an upright at each corner thereof and horizontally disposed and upwardly inclined bracing members secured to the uprights and extending longitudinally of the unit, an inclined endless sizing belt carried by said framework and extending upwardly from the receiving end 10 toward the discharge end thereof, a driving roller for the endless belt rotatably mounted on the framework, side panels positioned, one along each side of the upper run of said sizing belt and secured to the inclined bracing member and each 15 panel extending beyond the upper discharge end of said sizing belt with a part circumferential cut out portion extending around a part of the periphery of the driving roller, and means arranged between the upper and lower runs of said 20 sizing belt for discharging the articles passing through said belt, said unit having means whereby the two uprights at the receiving end of one unit are in contact with and secured directly to the two uprights at the discharge end of a second unit, and the forwardly projecting ends of the side panels of said second unit engaging with the side panels of the first unit and the side 25 panels of adjacent units being in substantial alignment, thereby to provide a multiple unit 30 separator.

2. A sizing apparatus comprising a plurality of similar units adapted to be used in connected series, each unit including a rectangular framework having an angle iron upright at each corner thereof and horizontally disposed and upwardly inclined bracing members secured to the uprights and extending longitudinally of the unit, an inclined endless sizing belt carried by said framework and extending upwardly from the receiving end toward the discharge end thereof, said receiving end lying within the confines of said framework and said discharge end extending beyond said framework, a driving roller for the endless belt rotatably mounted on the framework, side panels positioned, one along each side of the upper run of said sizing belt and secured to the inclined bracing member and each panel extending beyond the upper discharge end of said sizing belt and framework with a part 40 circumferential cut out portion extending around a part of the periphery of the driving roller, means arranged between the upper and lower runs of said sizing belt for discharging the articles passing through said belt, means for securing the transverse flanges of the angle iron uprights at 45 the receiving end of one unit in abutting contact with the transverse flanges of the angle iron uprights at the discharge end of a second unit and with the discharge end of the sizing belt of the 50 second unit overlying the receive end of the first unit, and means for securing the forwardly projecting ends of the side panels of said second unit with the side panels of the first unit thereby to provide a multiple unit separator, the side panels 55 of adjacent units being in substantial alignment. 60

WM. J. ZINK.
